END GATE FOR WAGON BOXES

Sherman Stekelenburg, Park Rapids, Minn.

Application October 14, 1952, Serial No. 314,611

2 Claims. (Cl. 296—51)

2

Figure 2 is a fragmentary side elevational view, taken from the right of Figure 1;

Figure 3 is an enlarged, fragmentary perspective view showing the construction at one of the upper corners of the extension plate;

Figure 4 is a sectional view taken substantially on line 4—4 of Figure 3;

Figure 5 is an enlarged, transverse sectional view taken substantially on line 5—5 of Figure 1;

Figure 6 is a sectional view taken substantially on line 6—6 of Figure 1;

Figure 7 is a fragmentary perspective view of the corner of the extension plate shown in Figure 3, illustrating the hinge strap thereof;

Figure 8 is a fragmentary perspective view showing one of the corners of the main wagon box; and

Figure 9 is a fragmentary perspective view showing one of the upper corners of the main plate, and illustrating the separable hinge connection of the main plate to the main box.

A generally conventional wagon box 10 has a flat floor 12, vertical side walls 14 projecting upwardly from the opposite longitudinal edges of said floor.

The end gate constituting the present invention includes a main end gate portion 16 and an extension end gate portion 18. The bottom edge of the main end gate portion 16 is adapted to rest upon a sill 20 (Figure 8) projecting rearwardly a short distance beyond the back edge of the floor 12, said main end gate portion 16 including a rectangular, flat main plate 22 the lower edge of which seats in an angular recess 24 defined by the floor 12 and sill 20 respectively.

Embracing the opposite, vertically extending side edges of the main plate 22 are angle iron reinforcements 26 bolted or otherwise fixedly secured to the main plate 22, and substantially coextensive in height with the main plate. Each reinforcement 26 has, at its upper end, a hinge strap 28 (Figures 5 and 9) extendable along the outer surfaces of the respective side walls 14 of the wagon box 10. In the lower edges of the hinge straps 28 are hinge slots 30 opening upon said lower edges, and adapted for engagement therein of removable hinge pins 32 projecting laterally and outwardly from the top edge portions of the respective side walls 14.

Separable hinge connections, whereby the plate 22 is pivotally attached at opposite ends of its upper edge of the main box of the wagon box 10, are thus provided.

Means for normally preventing swinging movement of the main plate 22 about said hinge connections includes a pair of vertical stakes 34 (Figure 1) mounted upon the outer surface of the main plate 22, for up and down sliding movement. Stakes 34 are removably engageable, at their lower ends, in stake-receiving pockets 36 secured to the sill 20.

To mount the stakes for sliding movement, bolts 38 (Figure 5) are extended through the main plate 22, and project through a longitudinal slot 40 formed in each stake. The bolts 38 also project through a connecting plate 42 overlying the stake and the slot 40 thereof. This construction permits each stake 34 to be shifted upwardly or downwardly, within the limits defined by slots 40, the up and down movement of the stake being guided by the bolts 38.

Means is provided for lifting the stakes 34 from their associated pockets 36, said means including links 44 pivoted at their upper ends upon the main plate 22, said links 44 being connected at their lower ends to the upper ends of operating levers 46, said levers 46 being pivoted, intermediate their ends, upon the respective stakes 34.

Thus, when the levers 46 are swung upwardly in the direction of the arrows shown in Figure 1, they will shift the stakes 34 upwardly, out of their associated pockets

This invention relates to an end gate for wagon boxes. More particularly, the invention refers to an end gate adapted for association with a wagon box of the type including a main box and an extension box adapted to be superimposed upon the main box to increase the depth thereof. The end gate constituting the present invention, summarized briefly, includes a main plate adapted to extend across and close one end of the main box, the main plate being coextensive in height with the depth of the main box and having a separable hinge connection, at opposite ends of its upper edge, to the opposite sides of the main box. Adapted to be superimposed upon the main plate, in substantially coplanar relation thereto, is an extension plate, adapted to extend across and close the corresponding end of an extension box, the extension plate having a separable connection to the main plate for the purpose of joining the plates to form a single unit. The extension plate, at opposite ends of its upper edge, has a separable hinge connection to opposite sides of the extension box. Thus, when the main and extension plates are fixedly connected, they swing as one upon the hinge connections of the extension plate. When, however, the extension plate is removed, together with its associated extension box, the main plate can swing upon its separable hinge connection to the main box. Stake means are associated with the main plate, and are removably engageable in stake-receiving pockets of the main box, so as to hold either the main plate or the main and extension plates against swinging movement on the selected hinge connections.

Important objects of the invention are as follows:

First, to provide an end gate construction which is adapted to be used either as a swingable closure for a conventional wagon box, or as a swingable closure for a conventional wagon box having an extension box superimposed thereon;

Second, to provide an end gate construction wherein the main and extension plates can be swiftly assembled with one another, and disassembled from one another with equal speed and facility;

Third, to provide an end gate construction which will be rugged, durable, and yet comparatively inexpensive so far as the manufacturing costs thereof is concerned;

Fourth, to provide an end gate wherein the main plate can have associated therewith a slidable closure, which closure will function with equal effectiveness whether or not the extension plate is being used; and

Fifth, to provide an end gate which will be substantially trouble free in operation, and will require a minimum of maintenance.

Other objects will appear from the following description, the claims appended thereto and from the annexed drawing, in which like reference characters designate like parts throughout the several views, and wherein:

Figure 1 is a rear elevational view of a wagon box and of an end gate formed in accordance with the present invention;

36. This allows swinging movement of the main plate 22 upon the hinge pins 32.

The main plate 22 is provided, intermediate its opposite side edges, with a vertically slideable closure 50, the opposite side edges of which are received in grooved guide rails 52 (Figures 1 and 6), bolted to the main plate. Links 44, it may be noted, are pivotally connected at their upper ends to said guide rails to provide for the pivotal mounting of said links upon the main plate.

To lift the slideable closure 50, I provide levers 54 pivotally attached at their upper ends to the respective guide rails 52, and pivotally connected intermediate their ends to the freely swingable upper ends of links 56, that are pivotally attached at their lower ends to the closure 50. Upward swinging movement of the levers 54, in the direction of the arrows shown in Figure 1, transmits upward movement to the slideable closure 50.

If the wagon box 10 is being used without an extension box, only the main plate 22 would be utilized, said plate swinging upon the hinge pins 32. However, if an extension box is superimposed upon the main box, the extension end gate portion 18 is also utilized.

The extension end gate portion 18 includes an extension plate 58 adapted to be positioned above the main plate 22, with the top edge of the main plate 22 in contact with the bottom edge of the extension plate, and both plates arranged in coplanar relation (Figure 5).

The opposite side edges of the extension plate 58 have bolted thereto angle iron reinforcements 60 provided, at their upper ends, with forwardly directed hinge straps 62 (Figures 3 and 7). The hinge straps 62 are slotted as at 64 to receive hinge pins 66, said hinge pins 66 projecting laterally and outwardly from the opposite sides of the extension box. The extension box has, at its opposite sides, vertically disposed stakes 68 notched as shown in Figure 3 to receive the hinge straps 62, thus to provide clearance for swinging movement of the end gate. It may be noted at this point that the main box also has stakes notched at their upper ends, to receive the hinge straps 28 of the main plate.

The opposite sides of the extension box have been designated at 70, the hinge pins 66 projecting through the sides 70 and through the stakes 68.

Formed upon the lower end of each angle iron reinforcement 60 is a laterally and outwardly projected, apertured ear 72 aligned vertically with a corresponding ear 74 formed upon the upper end of the adjacent angle iron reinforcement 26. Connecting bolts 76 are removably insertable through the respective ears 72, 74, to fixedly connect the extension and main plates.

When the extension and main plates are fixedly connected, depending cleats 78, secured to opposite faces of the extension plate 58, extend downwardly to straddle the top edge of the main plate 22, thus to cooperate with the connecting bolts 76 in rigidifying the attachment of the main and extension plates to one another.

Assuming that the extension box and extension end gate portion 18 are to be used, the hinge pins 32 would first be removed, after which the connecting bolts 76 are inserted. The entire end gate now swings upon the hinge pins 66, but is still held in a normally closed position by the stakes 34 carried by the main plate 22.

In the case where the wagon box 10 is to be used without an extension box superimposed thereon, the extension end gate portion 18 will be removed from the main end gate portion so that there will be an operative pivotally openable closure provided by the hinge pins 32, since to remove the end gate extension 18, it is merely necessary to remove the bolts 76 and lift the extension 18 off the main end gate portion 16 after the hinge pins 32 have been removed, and the hinge pins will then be reinserted so that the main end gate portion will hingedly swing about the pins 32 as an axis permitting the main end gate portion 16 to move in an arcuate path from

an open to a closed position with relation to the wagon box.

From the foregoing it will be apparent that there has been provided in a wagon box of the type having a horizontal floor and mounting an end gate at one end thereof for movement in an arcuate path about an axis spaced from the floor from a closed to an open position, a pair of stakes 34 in spaced parallel relation to each other and carried by the end gate and arranged to move in parallel rectilinear paths intersecting the arcuate path in which the end gate moves, a pair of stake-receiving pockets 36 carried by the wagon box in spaced relation to each other to receive respective ones of the stakes 34 when the stakes are moved in their respective rectilinear paths to intersect the arcuate path of said end gate for securing the end gate in its closed position, guide rails 52 are carried by the end gate in spaced parallel relation to each other and in spaced parallel relation to the stakes 34 to receive the opposite edges of the slideable closure 50 therein and a pair of levers 54 for lifting the closure with each of the levers 54 pivotally attached intermediate its ends to respective guide rails 52 and pivotally connected at its lower end to the respective guide rails 52, and means to move the stakes including the pair of levers 46, each lever 46 being pivotally mounted at one end on the stake 34 for movement in an arcuate path perpendicular to the arcuate path of the end gate and pivotally connected intermediate its ends to one of the guide rails 52.

In the case where the extension box is employed, this invention provides an end gate for the wagon box having a main plate 22 extending across one end of the main wagon box and provided with an extension plate 58 superimposed upon and releasably secured to the main plate 22 in coplanar relation thereto, the main and extension plates in their secured relation are mounted on the extension box for movement in an arcuate path about an axis spaced from and transversely of the floor 12 of the wagon box 10 from a closed to an open position. The stakes and the slideable closure will operate in the same manner as when the extension box and extension plate are not employed with the wagon box 10.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. In a wagon box of the type having a horizontal floor and mounting an end gate at one end thereof for movement in an arcuate path about an axis spaced from said floor from a closed to an open position, a pair of stakes in spaced parallel relation carried by said end gate and arranged to move in parallel rectilinear paths intersecting the arcuate path in which the end gate moves, a pair of stake-receiving pockets carried by said wagon box in spaced relation to each other to receive respective ones of said pair of stakes when said stakes are moved in their respective rectilinear paths to intersect the arcuate path of said end gate for securing the end gate in its closed position, a pair of parallel guide rails carried by said end gate between and in parallel relation to said stakes, a slideable closure having its opposite edges received in said guide rails, a pair of levers for lifting said closure, each lever of said pair pivotally attached intermediate its ends to said closure and pivotally connected at its upper end to an adjacent guide rail, and means to move said stakes in their rectilinear paths.

2. An end gate for a wagon box having a horizontal floor, a main box and an extension box, comprising; a main plate extending across one end of said main box, an extension plate superimposed upon and releasably secured to said main plate in coplanar relation thereto, said main and extension plates mounted on said extension box for movement in an arcuate path about a common axis adjacent the upper end of said extension plate and transversely of said floor from a closed to an open position, a pair of stakes in spaced parallel relation carried by said main plate and arranged to move in parallel rectilinear paths intersecting the arcuate path in which the main and extension plates move, a pair of stake-receiving pockets carried by said wagon box in spaced relation to each other to receive respective ones of said pair of stakes when said stakes are moved in their respective rectilinear paths to intersect the arcuate path of said plates for securing the plates in their closed position, a pair of parallel guide rails carried by said main plate between and in parallel relation to said stakes, a sliding closure having its opposite edges received in said guide rails, a pair of levers for lifting said closure, each of said pair pivotally attached intermediate its ends to said closure adjacent opposite sides thereof and pivotally connected at its upper end to an adjacent one of said guide rails, and means to move said stakes in their rectilinear paths.

5

10

15

tion, a pair of parallel guide rails carried by said main plate between and in parallel relation to said stakes, a sliding closure having its opposite edges received in said guide rails, a pair of levers for lifting said closure, each of said pair pivotally attached intermediate its ends to said closure adjacent opposite sides thereof and pivotally connected at its upper end to an adjacent one of said guide rails, and means to move said stakes in their rectilinear paths.
